UNITED STATES PATENT OFFICE.

HENRY B. SAUERMAN, OF CHICAGO, ILLINOIS

EXCAVATING APPARATUS.

1,269,921.

Specification of Letters Patent. Patented June 11, 1918.

Application filed February 8, 1918. Serial No. 216,806.

To all whom it may concern:

Be it known that I, HENRY B. SAUERMAN, a citizen of the United States, residing at Chicago, in the county of Cook and State of Illinois, have invented a new and useful Improvement in Excavating Apparatus, of which the following is a specification.

My invention relates, more particularly, to excavating apparatus, of the type employing scraper-buckets, in which the bottom of the scraper is connected with the body-portion thereof in a manner to permit the bottom to swing relative to said body-portion to a position in which the load is dumped.

As scrapers of this type have hitherto been constructed, the connections between the bottoms thereof and their body-portions, and portions of the operating mechanism, are so positioned that they do not extend clear of the sides of the excavation and the material being operated on and as a consequence, become clogged with the material which impairs the operation of the apparatus.

My primary object is to overcome the disadvantages above pointed out and to accomplish this by a simple and positively operating construction.

Referring to the accompanying drawings: Figure 1 is a broken view in side elevation of excavating apparatus constructed in accordance with my invention, the apparatus being shown in filling position. Fig. 2 is a similar view showing the parts in dumping position. Fig. 3 is a plan view of the scraper. Fig. 4 is a view like Fig. 1 of another form in which my invention may be embodied. Fig. 5 is a similar view showing the parts in dumping operation. Fig. 6 is a view like Fig. 1 of still another form in which my invention may be embodied, the parts being shown in filling position; and Fig. 7, a plan view of the scraper of Fig. 6.

Referring to the construction shown in Figs. 1, 2, and 3, 8 represents a cable-way such as is commonly used in apparatus of this general type and which is supported to extend across the material to be moved, this cable-way usually being so supported as to permit it to be slackened or made taut at will. Slidably mounted on the cable-way 8 is a carriage 9 which may be of any suitable

construction, that shown comprising a pair of side frames 10 (one only of which is shown), which are spaced apart at opposite sides of the cable-way 8 and are connected together, as for example by the cross-pins 11, to 18 inclusive, with suitable spacers between these frames to hold them separated, as is common in constructions of this general character, the pins 11 and 18 forming supports for sheaves 19 and 20, respectively which rest upon the cable-way 8.

The scraper-bucket in accordance with the preferred illustrated embodiment of my invention, is formed of a body-portion and a bottom, the body-portion being formed of sections 21 and 22. The section 21 is formed of the side plates 23 and end plate 24 and the section 22 is formed of the side plates 25. The bottom of the scraper is represented at 26 and is shown as connected with the plates 25 and with upright levers 27 and is provided with the cutting edge 26^a. The section 21 is provided with a pair of upwardly and forwardly projecting bars 28 which extend forwardly beyond the scraper at opposite sides thereof as shown, and to these bars, the outer ends of which are deflected at 29, the levers 27 are pivoted between their ends, as indicated at 30, the parts being so arranged that when in one position of the parts, viz., that shown in Fig. 1, the bucket will be closed at its sides and bottom as shown in this figure.

The bucket-section 21 is hung from the carriage, as by the cable 31 which connects with the pin 14 and with a bail 32 on the bucket and a cable 33 connected with the pin 15 and with a cross-piece 34 secured on a frame 35 carried on a bar 36 connecting the outer ends of the levers 28. The upper ends of the levers 27 are connected with cables 37 which are connected with and wound upon, sheaves 38 fixed on a shaft 39 journaled in the frame 35, this shaft carrying a larger sheave 40 upon which is wound, and to which is secured, a cable 41, cables 42 and 43 connecting the cable 41 with the carriage 9 at the pin 16 and with the scraper at 44, 100 respectively.

In the operation of the apparatus, the parts thereof are held in the filling and carrying position shown in Fig. 1 and the

scraper apparatus drawn along the cable-way, by pulling on the hauling line which in effect, comprises the cables 37 and 41 with the intermediate sheave mechanism described 5 and the steadyng cables 42 and 43. After the scraper, by being pulled over the material to be moved, becomes filled and drawn to the point of discharge by operating the hauling line, the operator slackens the hauling line, thus permitting the parts to swing 10 to the position shown in Fig. 2 in which the contents of the scraper freely slide from it, it being understood that at the time of dumping, the cable 8 must be in such taut 15 condition that the scraper extends clear of the ground beneath it. When the hauling line again is drawn taut, the parts return to the position shown in Fig. 1. In the particular system shown, a pull-back cable is 20 shown at 45 for returning the scraper to the point at which loading is to take place, but it will be understood that where the inclination of the cable-way 8 is sufficiently great to permit of the return of the scraper 25 by gravity to the filling point, such cable may be omitted.

In the construction illustrated in Figs. 4 and 5, the scraper-section 21, instead of having the levers 28, carries a bail 46 at its forward edge, at which it is supported from the carriage 9 by a cable 47, the cable 31 supporting the scraper-section 21 at its rear end. The sides of the bail 46 carry forwardly-projecting ears 48 which 35 overlap the sides 25 and to which the latter are pivoted at 49. The bail 46 has pivoted thereto, a forwardly-projecting latch-lever 50 with a shoulder 51 coöperating with the outer, roller-equipped, end of a yoke 52 carried by the scraper sides 25.

The hauling line is formed of the section 53 connected with a block 54, and the branch sections 55 and 56 connected with said block and with the carriage 9 and scraper at the 45 yokes 57 and 58, respectively. A cable 59, connected with the outer end of the latch-bar 50, runs over a pulley 60 journaled on the cross-pin 16, thence around a pulley 61 on the block 54 and connects with a sliding 50 block 62 supported at a pulley 63 thereon, on the cable-way 9, this block coöperating with a stop 64 on the cable-way at the point at which dumping is to be effected.

In the filling and load-carrying positions, 55 the parts are as illustrated in Fig. 4, in which position the latch-shoulder 51 engages the member 52 and prevents the scraper-section 22 from swinging to dumping position. As soon as the block 62 strikes the stop 64, it 60 causes the cable 59 to move and lifts the shoulder 51 free of the member 52, as shown in Fig. 5 which permits the parts of the scraper to swing to the positions illustrated in this figure, wherein the load discharges from the

scraper. As soon as the scraper apparatus 65 is returned to the point at which filling is to take place, the member 52 becomes interlocked with the latch-shoulder 51 and the parts are again in a position for filling.

The construction illustrated in Figs. 6 and 7 is the same as that shown in Figs. 1, 2, and 3, except that, instead of providing the differential sheave-mechanism in the hauling line, the hauling-line section 41 extends partially around a sheave 65 mounted in the 75 frame 35 and connects with the upper ends of the levers 27, this construction operating as described of the construction shown in Figs. 1, 2, and 3.

While I prefer to form the apparatus with 80 the sides 25 connected with the bottom 26 to move therewith as shown, this is not essential so far as certain features of my invention are concerned. Furthermore, other alterations and modifications may be made 85 without departing from the spirit of my invention, it being my intention to claim my invention as fully and completely as the prior state of the art will permit.

What I claim as new and desire to secure 90 by Letters Patent is—

1. A scraper-bucket formed of sections pivoted together, one being a body-portion and the other a bottom therefor, said bottom carrying upwardly extending members arranged at an angle to said bottom and to the upper portions of which adjacent the upper edge of said body portion said bottom is pivoted to said body-portion.

2. A scraper-bucket formed of sections 100 pivoted together, one being a body-portion and the other a bottom therefor, said body-portion carrying forwardly-extending members projecting beyond said body-portion, and said bottom being provided with members arranged at an angle to said bottom, with the pivotal connection for said sections located between said members on said body-portion and on said bottom.

3. In an excavating apparatus, the combination of a support, a scraper-bucket formed of sections pivoted together, one being a body-portion which carries an extension beyond its end and the other a bottom for said body-portion with an upward extension, the 110 pivot for said sections being between said extensions, and supporting means connected with said body-portion at one side of said pivot and with the extension thereof at the opposite side of said pivot.

4. In an excavating apparatus, the combination of a support, a scraper-bucket formed of sections pivoted together, one being a body-portion and the other a bottom for said body-portion having an upward extension, 120 with the pivot for said sections engaging said extension short of its upper end, means for supporting said body-portion, and means

for holding said bottom closed, connected with the upper end of said extension.

5. In an excavating apparatus, the combination of a support, a scraper-bucket formed of sections pivoted together, one being a body-portion and the other a bottom for said body-portion having an upward extension,

with the pivot for said sections engaging said extension short of its upper end, means for supporting said body-portion, and a ¹⁰ hauling-line connected with the upper end of said extension and operating when drawn taut to hold said bottom closed.

HENRY B. SAUERMAN.
